UNITED STATES PATENT OFFICE

172,530

RADIAL ARM POWER TOOL FOR ROTARY SAW OR THE LIKE

Dorr D. Beale, Minneapolis, Wilbert E. Johnson,
Forest Lake, and Robert L. Allen, Minneapolis,
Minn., assignors to Shopmaster, Inc., Minne-
apolis, Minn., a corporation of Minnesota

Application April 29, 1953, Serial No. 24,758

Term of patent 14 years

(Cl. D93—3)

To all whom it may concern:

Be it known that we, Dorr D. Beale, Wilbert E. Johnson, and Robert L. Allen, all citizens of the United States, residing at Minneapolis, Forest Lake, and Minneapolis, State of Minnesota, have invented a new, original, and ornamental Design for a Radial Arm Power Tool for Rotary Saw or the like, of which the following is a specification, reference being had to the accompanying drawings, forming a part thereof:

Fig. 1 is a top plan view of the radial arm power tool for rotary saw or the like, embodying our new design;

Fig. 2 is a front elevational view thereof;

Fig. 3 is a rear elevational view thereof;
Fig. 4 is a left side elevational view thereof; and
Fig. 5 is a right side elevational view thereof.

The essential features of our design reside in the portions shown in full lines.

We claim:

The ornamental design for a radial arm power tool for rotary saw or the like, substantially as shown and described.
